FOLDING CHAIR

Morton D. Rechler, New York, N. Y., assignor to
 Rexart Metal Industries, Inc., New York, N. Y.,
 a corporation of New York

Application January 11, 1950, Serial No. 137,937

4 Claims. (CL. 155—105)

1

This invention relates to folding chairs, one of the objects being to provide a light weight comfortable chair easy to open and close and requiring small space for storing and shipping.

Another object is to produce a chair of this type which will give as near as possible the appearance and comfort of a chaise longue, with the added advantage of foldability and grace of lines.

Another object is to provide a framework in which the several parts move automatically in timed relation to open and close the chair by a single folding action.

Another object is to provide simple means enabling the back frame to be adjusted to three different positions, and wherein these adjustments may be made easily while seated in the chair.

A further object is to provide a fabric covering which may be attached to the framework of the chair with a minimum of labor, and which enables easy renewal.

Various other objects and features of advantage will be apparent as the description proceeds, reference being made to the accompanying drawings in which:

Fig. 1 is a perspective view of the chaise longue folding chair made according to my invention.

Fig. 2 is a front view of an arm rest and adjustable linkage.

Fig. 3 is a vertical section on the line 3—3 of Fig. 2.

Fig. 4 is a vertical section on the line 4—4 of Fig. 3.

Fig. 5 shows the linkage moved to an intermediate position.

Fig. 6 shows the linkage swung to its rearmost position.

Fig. 7 is a side elevation of the chair illustrating the three positions of the back frame.

Fig. 8 is a perspective view of the partly folded framework with the covering fabric removed.

Fig. 9 is a perspective view of the chair with the covering in place and the framework folded to occupy small space.

Fig. 10 is a detail of a pivot plate and associated frame members.

Fig. 11 is a perspective layout of the fabric chair covering.

Fig. 12 is a cross-section on the line 12—12 of Fig. 1.

Fig. 13 is a cross-section on the line 13—13 of Fig. 1.

Fig. 14 is a cross-section on the line 14—14 of Fig. 1.

2

Fig. 15 is a cross-section on the line 15—15 of Fig. 1.

Fig. 16 and Fig. 17 are modified forms of fasteners.

5 Fig. 18 is a cross-section of a round frame and fastening means.

In the drawings the numeral 10 designates a chair embodying the invention and including in its general construction a seat frame 11, back frame 12, front leg frame 13, rear leg frame 14, foot-rest frame 15, foot-rest support 16, armrests 17, back adjusting linkage 18, and chair covering fabric 19, there being operating means which act in timed relation to fold the chair into the compacted condition shown in Fig. 9 after the folding has passed through the intermediate stage shown in Fig. 8.

The frames are made preferably from light weight metal stock such as aluminum, in the present example of square cross-section which may be easily bent, shaped as required, and worked to close tolerances to obtain close fits and compactness of the frame structure. The seat frame 11 may be in the form of a pair of side members 20 having at their forward ends 21 the pivot bolts 22 and short links 23 by means of which pivotal connections are made to the rearwardly extending ends 24 of the foot-rest frame 15. The rear ends 25 of the seat frame 11 are connected by pivot bolts 26 to the swingable pivot plates 27 which in turn are attached by pivot bolts 28 to the lower ends 29 of the back frame 12.

The upper ends 30 of the rear leg frame 14 are connected by pivot bolts 31 to the pivot plates 27, and, in the open position of the chair a web 32 engages the rear leg frame 14 below its pivot to hold said frame in its position of use. Cross bolts 33 extending between the sides of the pivot plates engage the upper surface of the seat frame 40 at 35 to hold the pivot plates at a predetermined angularity with respect to the seat frame.

The front leg frame 13 is pivoted at 37 to the seat frame 11, the upper ends 36 of the leg frame 13 being above the pivots 37 whereby forward and rearward movement imparted to the upper ends 36 swings the lower portion 39 of the front leg frame toward or away from the rear leg frame 14 during the closing and opening operations of the chair. Spacing washers as at 38 may be used between the frames.

Means of connection such as radius rods 40 have pivotal attachment at 41 to the rear leg frame 14 below pivots 31, and also have similar pivotal connections at 42 immediately below or

adjacent to the upper ends 36 of the front leg frame 13. Connecting rods 43 are pivoted at 44 below pivots 37 and extend forward and slightly upward to pivotal connections 45 with foot-rest frame 15, which latter is connected by plates 46 and bolts 47 to the upper ends 43 of the support 16.

Secondary rods 49 are pivotally connected at one end 50 to the support 16 below the pivot bolts 47, and at their other ends to pivots 51 mounted in plates 52 secured to connecting rods 43.

The rear portions 53 of the arm-rests 17 are pivoted to the rising side rails 54 of the back frame 12 by suitable means such as screws 9. The forward ends 55 of the arm-rests carry on their under faces 56 brackets 57 secured as by screws 8 (Figs. 2 and 3). The brackets 57 preferably comprise U-shaped pieces including the side walls 58 and the mounting base 59, through which the screws 8 pass into the arm-rests 17. Each bracket is provided with a pair of parallel link plates 60 drilled at one end 61 for passage of pivot bolts 62 which extend through bayonet slots 63 in the opposite side walls 58 of the brackets. In the present case each of the link plates 60 has a projection 64 which may be brought into engagement with an abutment formed by a cross bolt 65 fastened between the walls 58 of the bracket. There is a wide spacing washer 66 between the plates 60. A bolt 67 pivotally connects the opposite end 68 of the plates 60 to the upper ends 36 of the leg frame 13. Notches 6 engage upper ends 5 of rods 40.

Figs. 1 and 3 show the position of the arm-rests 17 and link plates 60 when the back frame 12 is in sitting position. The occupant of the chair can move the arm-rests rearward to swing the back frame to the intermediate position shown in Fig. 4. This brings the projection 64 into engagement against the abutment bolt 65 stopping further rearward turning of the link plates about the axis of bolt 67 at the top of the front leg frame 13. Should the occupant desire to move the back frame to the full reclining position he will lift the arm-rests slightly forward and upward as shown by dot-dash lines and arrow x in Fig. 5. This allows pivot bolt 62 to shift out of the offset upper notch 70 and to ride down into the lower notch 71 of the bayonet slot 63 so that the projection 64 can clear the abutment 65 when the link plates and their associated arm-rests are moved toward the back of the chair. As shown in Fig. 6 this movement is arrested when the edges 72 of the link plates come into engagement with the abutment 65. To return to sitting position the occupant leans forward and the back automatically returns with him as the linkage rotates to the front due to the forward shifting of the occupant's weight from the back to the seat portion of the covering 19. The three adjustments of the back are shown in Fig. 7, wherein the reference letters A, B, and C indicate the sitting, intermediate, and full reclining positions respectively, and it will be noted in Fig. 4 that sufficient clearances are provided to insure easy operation of the movable parts of the linkages without binding.

The seat covering 19 may be constructed as shown in Fig. 11 wherein a length of duck or other fabric 75 is provided at its opposite ends 76 and 77 with snap fastener elements 78 adapted to engage openings 79 in the cross bar 80 forming the top of the back frame 12 and similar openings 81 in the foot-bar 82 of the foot-rest 15. Enough material is allowed by margins 83 and 84

to wrap around the bars 80 and 82 so that a good grip is obtained to hold the fabric in place.

The covering may include a head cushion 85, back cushion 86, seat cushion 87, and foot-rest cushion 88. The back portion 89 is provided with a back strap 90 which fits tightly over the side rails 54 of the back frame 12. Lines of stitches 7 are suitable for securing the back strap to the fabric and to the cushion 86 as in Fig. 12. The fabric at 91 supporting the seat cushion 87 has a cross strap 92 comprising two tabs 93 and 94. Each may have a line of grommets 95 adapted to be brought together beneath the seat frame 11 as indicated in Fig. 13 and fastened by hooks 96 passed through the grommets. The foot-rest cushion 88 is similarly held in place by tabs 97 and 98 brought around the bar 82 and held by hooks 99 through marginal grommets 100. The covering is placed on the chair frame by slipping the back strap 90 downward over the rails 54 of the back frame 12 leaving enough slack as indicated by the dot-dash lines in Fig. 14 to allow the marginal material 83 to be worked around the cross bar 80 and the snap elements 78 to be snapped into the openings 79. The back strap 90 is next pushed downward on the rails to tighten the material 83 around the bar 80, and it is this tight frictional grip of the back strap against the back frame that prevents the wound margin 83 from backing loose on the cross bar 80. The other margin 84 may be similarly attached by providing a line of fasteners 73 on the end 71, winding around bar 82, and snapping the fasteners into the openings 81. This is followed by hooking together the tabs beneath the seat and foot-rest frames.

Fig. 16 is a modified fastener comprising a stud 101 riveted through the fabric 102 and is designed to be inserted into such openings as 79 or 81. A further substitute is shown in Fig. 17 wherein a stud 103 projects through a grommet 104 in the fabric 105. Any of these fasteners may be used with the square bar of Fig. 14 or the round bar of Fig. 18.

The chair is folded by the simple operation of moving the seat frame upward toward the back frame, a convenient bar 106 being provided adjacent the front end of the seat frame accessible through an opening 107 in the fabric for one of the hands of the operator while the other hand grasps the back frame. During this motion the front leg frame 13 moves about its pivots 37 and folds rearward toward the back frame as seen in Fig. 8, while the rear leg frame 14 moves forward and upward passing through the loop of the front leg frame by operation of the radius rods 40. The pivot plates 27 move about their pivots 28 to the back frame, and in timed relation the connecting rods 43 swing the foot-rest frame 15 toward the seat frame. The secondary rods 49 swing the foot-rest support 16 against the bottom of the foot-rest frame as it moves toward the seat frame, and finally all of the frames reach the compacted relation shown in Fig. 9. The reverse of this operation opens the chair for use. In Fig. 8 the fabric covering has been removed to give a clear picture of the operation of the framework. This covering is preferably of the sling type as shown in the drawings and acts through shifting body weight to return the chair to sitting position from either of the two positions of inclination shown in Figs. 5 and 6.

It is further to be noted that when the linkages have moved with the back frame to sitting position (Fig. 3) the pivot bolts 62 have swung past and

to a point below the dead center position indicated by dot-dash line 2, and the linkages thus form overlocks to hold the back frame in sitting position.

When the linkages have been rotated rearwardly to the position indicated in Fig. 6, the pivot bolts 62 have not passed the dead center line 2 and will remain above that line with the edge 72 in engagement with abutment 65 until the occupant shifts position as explained to throw the linkages forward. This forward rotation of the linkages about the axis bolts 67 is arrested when the notches 6 engage the upper ends of the rods 48 which act as stops to clear the arm-rest from the underlying framework while at the same time allowing the pivot bolts 62 to reach their overlocking positions below line 2.

The chair portion of this new folding chaise longue is of the general kind shown in my Patent No. 2,467,909, issued April 19, 1949, the folding parts of that chair being well adapted for use as elements in the new organization. The interconnected chair frames and foot-rest mechanism are so interrelated by their pivotal connections and operating rods that they fold and unfold in timed relation by simple manipulation of the seat and back frames. Various modifications may be made within the scope of the following claims.

I claim:

1. A folding chair comprising in combination a seat frame, a front leg frame pivoted between its upper and lower ends to the sides of the seat frame, a rear leg frame, a back frame, pivotal means of connection between the seat frame, the rear leg frame and the back frame, a radius rod pivoted to the rear leg frame and extending forward to pivotal connection with the front leg frame above its pivot to the seat frame, a foot-rest frame pivoted to the forward ends of the seat frame, a connecting rod pivoted at one end to the front leg frame below its pivot to the seat frame and having pivotal connection at its other end to the foot-rest frame, a foot-rest support pivoted to the foot-rest frame, a secondary rod pivotally secured at one end to the foot-rest support and at its other end between the pivots of the connecting rod, and arm-rests pivoted at their rear ends to the back frame and having pivotal means of connection at their forward ends to the upper ends of the front leg frame, the folding parts of the chair moving automatically to closed and opened positions by swinging the seat frame toward and away from the back frame.

2. A folding chair comprising in combination a seat frame, a front leg frame pivoted between its upper and lower ends to the sides of the seat frame, a rear leg frame, a back frame, pivotal means of connection between the seat frame, the

rear leg frame and the back frame, a radius rod pivoted to the rear leg frame and extending forward to pivotal connection with the front leg frame above its pivot to the seat frame, a foot-rest frame pivoted to the forward ends of the seat frame, a connecting rod pivoted at one end to the front leg frame below its pivot to the seat frame and having pivotal connection at its other end to the foot-rest frame, a foot-rest support pivoted to the foot-rest frame, a secondary rod pivotally secured at one end to the foot-rest support and at its other end between the pivots of the connecting rod, and arm-rests pivoted to the back frame, and adjustable linkages connecting the front ends of the arm-rests to the upper ends of the front leg frame enabling the back frame to be adjusted to different positions of inclination, the folding parts of the chair moving automatically to closed and opened positions by swinging the seat frame toward and away from the back frame.

3. A folding chair according to claim 2, in combination with a sling type chair covering extending from the upper part of the back frame to the front end of the foot-rest frame.

4. A folding chair including a seat frame, a front leg frame pivoted between its upper and lower ends to the seat frame, a foot-rest frame pivoted to the forward end of the seat frame, a connecting rod pivoted at one end to the front leg frame below its pivots to the seat frame and having pivotal connection at its other end to the foot-rest frame, a folding support pivoted to the foot-rest frame, a secondary rod pivotally secured at one end to the folding support and at its other end between the pivots of the connecting rod, the foot-rest frame being adapted to fold about its pivot automatically to closed position beneath the seat frame when the front leg frame is moved rearwardly about its pivot.
